UNITED STATES PATENT OFFICE

FRED R. ZIMMERMAN, OF CHICAGO, ILLINOIS, ASSIGNOR, BY MESNE ASSIGNMENTS, TO BURTON-DIXIE CORPORATION, OF CHICAGO, ILLINOIS, A CORPORATION OF DELAWARE

SPRING MATTRESS ASSEMBLY

Application filed July 16, 1930. Serial No. 468,317.

My invention pertains to certain mechanical and functional betterments in spiral-spring assemblies, such, for example, as those used in spring mattresses.

5 One object of the invention is to provide a spring structure of this or similar character which will possess adequate and proper cushioning properties and which will retain such capacities for an unlimited period.

10 A feature of the invention is the employment of relatively-small, upright springs at the corners of the construction and at points along the sides of the spring-assembly between the larger springs, whereby to fill in 15 the otherwise unoccupied spaces and thus to make a structure better fitted to do the intended work.

Another aim of the invention is to use a border wire along the margin or side of the 20 spring construction so formed that it will give great freedom of movement or compression of the neighboring upright springs and in such a manner that the wire will not become permanently bent or set.

25 Other advantages incident to the employment of the invention will become apparent to those skilled in the art from an understanding of the present preferred embodiment of the invention described in detail below and illustrated in the accompanying drawings, in the views of which, for simplicity, the same parts have been designated by like reference characters.

30 In these drawings,—
35 Fig. 1 is a fragmentary plan view of a corner portion of the spring-assembly; and

Fig. 2 is an elevation of the side of the same.

Referring to the drawings, it will be perceived that the spring-assembly comprises a number of cross rows of upright, hour-glass, spiral-springs 11, 11, the springs of adjacent rows being in staggered or offset relation, as is common practice and as is fully 45 shown in the drawings.

Inasmuch as the top and bottom of the structure are substantially alike, a full and complete description of the top will suffice for an understanding of the whole construction.

Each of such transverse rows of springs is connected to the springs of the rows on opposite sides of it by zigzag, cross wires 12, 12 joined in the manner shown to the top coils of the springs, such wires being alternately 55 interlocked with the upper convolutions or terminal coils 13, 13 of the springs of adjoining rows, such construction constituting the subject-matter of my co-pending application Serial No. 417,669, filed December 31, 60 1929.

At each corner of the assembly a smaller, upright, helical spring 14 is employed, the convolutions of which, with the possible exception of the end ones, are of substantially 65 the same size.

The end portion 15 of the wire forming the top of each such spring is wrapped around the upper convolution 13 of the adjacent, hour-glass spring 11 at the end of the structure, the terminal portion 16 of the wire, forming the bottom of such spring, being in similar manner wound around the bottom coil of the neighboring spring 11 at the side 75 of the spring-assembly.

Along the side of the construction, there are spaces at the ends of alternate, cross rows of springs 11, and each of such gaps is occupied by an erect, helical spring 17 of substantially the same size as the spring 14, the top, end coil 18 of the spring 17 being somewhat enlarged, with the end 19 of its wire interlocked with a crimped part 20 of the top coil 13 of the next spring 11 of the same cross row, the bottom, end coil of spring 17 being, in like manner, joined to the bottom, end coil of the same spring 11.

Along each end of the assembly, both at the top and bottom, a border-wire 21 is employed which is interlocked with the top and bottom, end coils of the springs 11 and 14 at the two ends of the structure.

Each such top or bottom wire coil of each end spring 11 is bent inwardly at 22, then outwardly at 23, then inwardly at 24, and again outwardly at 25, the two adjacent parts 23, 24 constituting, as is clearly depicted, an intermediate, outward extension, and the border-wire 21 is bent so as to pass over the top coil 13, below the part 22, over the sections 95 100

23 and 24, beneath the part 25, and again over the top coil 13.

Thus, the border-wire 21 is firmly and securely locked or attached to the top coils of 5 the springs referred to.

As is fully illustrated, like connections are made with the top coils of the corner springs 14, and the ends of the border-wire 21 are wrapped around the upper coils 13 of the 10 end springs of the next cross row at 26 and terminating in downturned or upturned ends 126, as the case may be.

In order that the appliance may have substantial and proper cushioning properties and 15 that it may retain such resilient characteristics unimpaired, it is desirable that the border-wires along the tops and bottoms of the sides have greater flexibility than the corresponding end border-wires 21, and, accordingly, 20 such side border-wires 27, 27, which are united with the end coils of the marginal springs 11 and 17 in a similar but reverse way to that by which the wires 21 are joined to the comparable springs, are corrugated or 25 crimped at 28 between the springs to give them adequate capacity for flexure and bending without danger of becoming permanently set.

Each such side wire 27 terminates in a 30 downturned or upturned end 127, depending upon whether it is a top or bottom border wire.

Obviously, such characteristic or distinctive feature of the side border-wires allows 35 substantial freedom of movement of the upright springs, and, upon release from the imposed load, all of the parts involved readily return to their original positions and relation.

40 Thus, there is a direct co-operation and co-action between the style of border-wire and the resiliency and flexibility of the spring-assembly as a whole and its capability for localized deflection and full return to initial 45 condition upon release from imposed strain.

From an understanding of what precedes, coupled with the illustration, it will be appreciated that the border or marginal portions of the spring-assembly have been adequately 50 supplied with sustaining, upright springs, and that no gaps or spaces of substantial size exist which would interfere with the comfort of the user, the life of the spring-assembly, or its satisfactory and sustained performance of its functions.

It will be noted that the end border-wires 55 21 extend around the corner springs 14, but that the side border-wires terminate short of the corner springs and have their ends coupled to the side springs 11 next to the corner springs.

In some cases, it may be preferable to form the end and side border-wires from a single length of wire, but, in other instances, it may 60 be desirable to have the individual side wires

separate from the individual end wires, as illustrated, in order that they may be of somewhat different gauge.

The employment of filler springs at frequent intervals along the sides of the structure, in association with the crimped features of the side border-wires, results in an assembly with marked cushioning characteristics along its sides and without danger of permanent distortion of any of the parts involved 75 in the construction.

It should be perceived also that the cross wires 12 which connect the larger, vertically-arranged springs together are not directly united with the smaller springs or with the border-wires, such arrangement aiding in giving the assembly the capacity for yielding in a manner to conserve the comfort of the occupant of the appliance.

This novel and improved construction 80 has been referred to as especially applicable for use in a spring mattress, but those acquainted with the art will readily understand that its principles of construction may be satisfactorily employed in bed springs.

The invention, as defined by the appended claims, is not necessarily limited and confined to the exact details of construction, and these may be modified within relatively wide limits without departure from the principles of the 95 invention and without the loss of any of its material advantages.

I claim:

1. In a spring-assembly, the combination of parallel rows of upright spiral-springs 100 with the springs of adjacent rows in staggered relation leaving gaps at corners of the assembly, means tying said springs together, smaller upright spiral-springs occupying said gaps at corners of the assembly, one end wire of each of such corner springs being wrapped around the corresponding terminal coil of the next spring of the same row, the other end wire of each of such corner springs being wound around the corresponding terminal coil of the adjacent spring of the next row, and border-wire means connected to the end coils of the marginal springs of said rows and of said corner springs.

2. In a spring-assembly, the combination of parallel rows of upright spiral-springs with the springs of adjacent rows in staggered relation leaving gaps at corners of the assembly, means tying said springs together, smaller upright spiral-springs occupying said gaps at corners of the assembly, one end wire of each of said corner springs being wrapped around the corresponding terminal coil of the next spring of the same row, the other end wire of each of such corner springs being wound around the corresponding terminal coil of the adjacent spring of the next row, filler spiral-springs smaller than said row springs occupying the spaces at the ends of alternate rows of said springs, the end wires 110 115 120 125 130

of said filler springs being connected to the corresponding terminal coils of the adjacent springs in the same row, and border-wire means connected to the end coils of the marginal springs of said rows, of said corner springs and of said filler springs.

3. In a spring-assembly, the combination of parallel rows of upright spiral-springs with the springs of adjacent rows in staggered relation leaving gaps at corners of the assembly, means tying said springs together, smaller upright spiral-springs occupying said gaps at corners of the assembly, one end wire of each of said corner springs being wrapped around the corresponding terminal coil of the next spring of the same row, the other end wire of each of such corner springs being wound around the corresponding terminal coil of the adjacent spring of the next row, filler spiral-springs smaller than said row springs occupying the spaces at the ends of alternate rows of said springs, the end wires of said filler springs being connected to the corresponding terminal coils of the adjacent springs in the same row, and border-wire means connected to the end coils of the marginal springs of said rows, of said corner springs and of said filler springs, said border-wire means along the sides of said assembly being of wave form between its points of attachment to the springs to increase the flexibility thereof.

4. In a spring-assembly, the combination of parallel rows of upright spiral-springs with the springs of adjacent rows in staggered relation, means tying said springs together, smaller upright spiral-springs at the corners of the assembly, and border-wire means connected to the end coils of the marginal springs of said rows and to the end coils of said corner springs, the wire forming one end coil of each of such corner springs being extended to and bent around the corresponding terminal coil of the next spring of the same row and at a point remote from the connection of said coil to said border-wire means, the wire forming the other end coil of each of such corner springs being extended to and bent around the corresponding terminal coil of the adjacent spring of the next row at a point remote from the connection of such terminal coil to said border-wire means.

In witness whereof I have hereunto set
55 my hand.

FRED R. ZIMMERMAN.
